CLAIM

The ornamental design for an electronic device charger, as shown and described.

DESCRIPTION

FIG. 1 is a front view of an electronic device charger showing my new design;

FIG. 2 is a rear view of the electronic device charger;
FIG. 3 is a left side view of the electronic device charger, a right side view being a mirror image thereof;FIG. 4 is a top view of the electronic device charger;
FIG. 5 is a bottom view of the electronic device charger;
FIG. 6 is a top front side perspective view of the electronic device charger with a charging port in an extended position;
and,

FIG. 7 is a top front side perspective view of the electronic device charger with the charging port in a retracted position. The broken lines present in the figures are included for the purpose of illustrating portions of the article that form no part of the claimed design.

1 Claim, 4 Drawing Sheets---
